UNITED STATES PATENT OFFICE.

ALLEN E. J. LUCKHURST, OF JERSEY CITY, NEW JERSEY.

REGISTERING DEVICE.

No. 895,098.

Specification of Letters Patent.

Patented Aug. 4, 1908.

Application filed November 17, 1906. Serial No. 343,870.

To all whom it may concern:

Be it known that I, ALLEN E. J. LUCKHURST, a citizen of the United States, residing at Jersey City, New Jersey, have invented certain Improvements in Registering Devices, of which the following is a specification.

The object of my invention is to provide a registering device of a relatively simple and inexpensive character, and available for recording the amounts of cash received for sales in stores or shops as a substitute for the expensive devices now employed for that purpose, although it can, if desired, be made of a size small enough to be carried in the pocket in order to permit the user to keep an accurate account of personal expenditures.

In the accompanying drawings:—Figure 1 is a front view of a registering device made in accordance with my invention and intended for use in shops or stores; Fig. 2 is a rear view of the same; Fig. 3 is a vertical sectional view of the machine; Fig. 4 is a transverse section on the line *a—a*, Fig. 3; Fig. 5 is a transverse section on the line *b—b*, Fig. 3; Fig. 6 is a transverse section on the line *c—c*, Fig. 3; Fig. 7 is a transverse section on the line *d—d*, Fig. 3; Fig. 8 is a sectional plan view on the line *e—e*, Fig. 3; Fig. 9 is a sectional view of the devices for securing and releasing the hands used in connection with the totaling dial of the machine, and Fig. 10 is a sectional view of a special form of registering device made in accordance with my invention and intended for pocket use.

My improved registering device may have a casing of any desired character, depending upon the size of the machine and the use for which it is intended. The machine shown in Figs. 1 to 8 of the drawings is intended for use in shops or stores and is of a relatively large size, its casing resembling that of a mantel clock, but the device is susceptible of being made on a much smaller scale, so that it can be inclosed in a casing similar to that of a watch and can be carried in the pocket. The registers of the larger size are intended to provide a cheap and acceptable substitute for the elaborate and expensive machines now used in shops and stores for the purpose of registering cash sales, and the registers of the smaller size are available for the purpose of registering the personal expenditures of the user.

The device has front and back plates, the front plate 1 having an annular rim 2 sur-

rounding the opening for exposing the primary registering dial 3, and the back plate 4 having an opening surrounded by a rim 5 for exposing the totaling dial 6, upon which is registered the sum of the amounts indicated by the successive operations of the primary pointer, this opening being, if desired, provided with a locked cover plate, in order that it may be shielded from the view of those not authorized to examine it.

The frame work of the device comprises four parallel plates 8, 9, 10 and 11, which are rigidly secured in their proper lateral relation to each other by means of transverse stay bolts 12 provided with suitable nuts bearing upon the various plates of the frame, these plates also providing proper bearings for the various spindles of the registering mechanism.

A spindle 13 has an operating wheel or knob 14, with milled periphery, which can be readily turned in either direction by the user, and to said spindle is secured a spur wheel 15 which meshes with an intermediate spur wheel 16 turning loosely upon a spindle 17, such intermediate spur wheel meshing with a spur wheel 18 secured to the spindle 19 of the primary pointer 20, which operates in conjunction with the primary dial 3, the latter being graduated from zero to ninety-nine, so that one rotation of the pointer 20 will represent one hundred cents.

Operating in conjunction with the pointer 20 is a lever 21 suitably mounted upon a transverse plate 22 of the frame and carrying a hammer 23 for striking upon a gong 24, the lever being also acted upon by a coiled spring 25, which tends to cause such action of the hammer.

The lever 21 projects through an opening 7 in the plate 8 and dial 3, and when the pointer 20 is approaching the limit of each of its revolutions in the direction of the arrow, Fig. 1, it strikes the projecting portion of said lever and moves it forwardly, thereby drawing back the hammer 23 and distending the spring 25, which, as soon as the pointer has passed the lever, restores the latter to its normal position, causing the hammer to strike the gong and indicate a full revolution of the pointer 20 and consequently an amount equal to one dollar. A transaction amounting to \$1.35 therefore necessitates one ring of the gong and a further movement of the pointer 20 to the graduation 35 on the primary dial, an amount in excess of \$2.00 ne-

cessitating two rings of the gong and a further movement of the pointer, and so on. After registering the amount of a sale the knob 14 is manipulated so as to turn the pointer 20 back to zero position, the lever 21 serving as a stop to arrest such backward movement when the zero point is reached.

In order to provide for indicating the total amount of a number of transactions, the following means are employed: Secured to the intermediate spur wheel 16, in any suitable manner, is a disk 26, which carries one or more spring-pressed pawls 27, (see Fig. 5) four of these pawls being represented in the present instance. These pawls engage with a ratchet wheel 28 which is secured to the spindle 17 and the latter also carries another ratchet wheel 29 which is engaged by one or more spring-pressed pawls 30, the latter being hung to the fixed plate 9 of the frame. Any forward movement of the pinion 16 is therefore transmitted to the spindle 17 through the medium of the disk 26, pawls 27 and ratchet wheel 28, but any back movement of said spindle 17 is prevented by engagement of the pawls 30 with the ratchet wheel 29, said pawls acting as detents. The spindle 17 has a spur pinion 31 which meshes with a spur wheel 32 secured to a spindle 33, the latter having a spur pinion 34 which meshes with a spur wheel 35 on a tubular shaft or hub 36 surrounding the spindle 17.

The spur wheels and pinions 31, 32, 34 and 35 are so proportioned that the hollow shaft or hub 36 will turn once for every one hundred revolutions of the spindle 17, the latter carrying a pointer 37 and the hub 36 carrying a pointer 38, which pointers operate, respectively, in connection with outer and inner graduated circles on the totaling dial 6, each circle being graduated from zero to ninety-nine, the outer circle representing cents and the inner circle representing dollars, the totaling dial being therefore capable of registering an amount up to one hundred dollars.

In order to increase the capabilities of the device so that it may register up to one thousand dollars, I may in some cases employ a disk 41 mounted upon a spindle 42 and having, equidistantly disposed on its face, numbers from zero to nine, as shown in Fig. 7, this disk being provided, on its back, with ten equidistantly disposed projecting pins 43, which are successively struck and moved forwardly by an arm 44 on the spur wheel 35, one complete revolution of the latter thereby effecting one-tenth of a rotation of the disk 41, so that the numerals upon the latter are successively exposed through an opening 45 in the dial plate 6.

The disk 41 can be reset by a knob 46 on the spindle 42 whenever the arm 44 is out of the path of the pins 43, and in order to provide for resetting the pointers 37 and 38 on

their spindles 17 and 36 I may employ the device shown in Fig. 9 and consisting of a pair of washers 47 and 48, the washer 47 being secured to the tubular shaft or hub 36, and the washer 48 being secured to the spindle 17, both of these washers being toothed or notched on their outer faces, as shown at 47^a and 48^a, respectively, Fig. 9, for engagement with a projecting lug or tooth 37^a or 38^a on its respective pointer 37 and 38, the lug of the pointer 38 being held in engagement with the notched face of the washer 47 by contact of the hub of said pointer with the back of the washer 48, and the lug of the pointer 37 being held in engagement with the notched face of the washer 48 by the pressure upon the hub of said pointer of a nut 49, which is adapted to the threaded end of the spindle 17 and has, in its face, notches or openings 50, so disposed as to require the use of a special key for operating the nut. When the nut is backed off, the pointer 37 and washer 48 can be moved outwardly upon the spindle 17 so as to permit the pointer 38 to be moved outwardly on the hub 36 sufficiently to clear the washer 47, and after said pointer 38 has been reset, the washer 48 can be restored to its normal position, the pointer 37 reset, and the parts again locked by screwing up the nut 49.

It will be evident that a registering device such as that forming the subject of my invention can be constructed as cheaply as an ordinary watch or clock, and hence will form not only an acceptable and economical substitute for the expensive cash registers now in use but also, when of small size, a handy device for being carried upon the person for keeping record of personal expenditures.

The casing of the registering device may, if desired, be mounted upon a base carrying a cash drawer, as shown by dotted lines in Fig. 3.

In carrying out my invention I may, in some cases, omit the pointer 37 and the graduated circle coöperating therewith, and use but a single totaling pointer for indicating dollars only, since the graduated circle used in connection with such single pointer may be so large in diameter that it will indicate fractional parts of a dollar with sufficient approach to accuracy, and it will also be evident that the use of the knob 14 and intermediate gearing as a means for operating the primary pointer 20 is not essential, since the pointer itself can be directly moved, or the knob 14 can be applied to the spindle 19.

An embodiment of my invention, simplified in construction, and intended for pocket use, is shown in Fig. 10. In this register only the totaling dial 6, the spindle 17, the hollow shaft 36, the pointers 37 and 38, the gears 31, 32, 34 and 35, the ratchets 28 and 29, the pawls 27 and 30, and the disk 26 are

used, the knob 14 being applied directly to the end of the spindle 17 and the entire mechanism being contained in a casing 51, similar to that of a watch.

5 I claim:—

1. A cash registering device having a manually operated primary pointer co-operating with a graduated dial, in combination with a lever which is struck and moved by said pointer only on each complete rotation of the same.
2. A cash registering device having a manually operated primary pointer co-operating with a graduated dial, in combination with a lever which is struck and moved by said pointer only on each complete rotation of the latter, and an alarm device actuated by said lever.
3. A registering device having a primary pointer coöperating with a graduated dial, in combination with a lever which is struck and moved by said pointer only on each complete rotation of the latter, said lever serving as a stop to prevent back movement 25 of the pointer beyond the zero position.
4. A registering device having a primary pointer operating in conjunction with a graduated dial in combination with a lever which is struck and moved by said pointer only on each complete rotation of the same, and a knob and gearing interposed between said knob and pointer, whereby said pointer can be turned by said knob in either direction.
5. A registering device having, in combination, a primary pointer and dial, a totaling pointer and dial, and gearing interposed between the totaling and primary pointers comprising means always in gear therewith, and connections whereby, after each forward movement of the primary pointer, the latter can be returned to zero

position without affecting the position of the totaling pointer.

6. The combination, in a registering device, of the totaling shaft or spindle, a pointer rotatable thereon and provided with a hub, a notched washer moving with the shaft or spindle, and means for retaining the hub of the pointer in engagement with the notched washer or permitting release of the same from engagement therewith.

7. The combination of the totaling dial spindle, the tubular shaft surrounding the same, pointers, one free to turn on the spindle and the other free to turn on the shaft, notched washers rotating respectively with the shaft and spindle, and a nut for retaining the spindle pointer in engagement with its washer, the latter retaining the other pointer in engagement with its washer.

8. A registering device in which are combined a primary pointer and a graduated dial representing cents, a spindle for said pointer, a totaling pointer and graduated dial representing dollars, a shaft for said pointer, gearing connecting said spindle and shaft, a ratchet and pawl mechanism interposed between the primary pointer and the totaling pointer for imparting movement to the latter, and ratchet and pawl mechanism for preventing back movement of the totaling pointer, whereby, after each forward movement of the primary pointer, the latter can be returned to zero position without affecting the position of the totaling pointer.

In testimony whereof, I have signed my name to this specification, in the presence of two subscribing witnesses.

ALLEN E. J. LUCKHURST.
